UNITED STATES PATENT OFFICE.

WESLEY J. VONDRACEK AND CYRIL C. SLAPNICKA, OF CEDAR RAPIDS, IOWA.

OIL-BURNER.

Specification of Letters Patent. Patented Aug. 20, 1912.

1,036,037.

Application filed November 27, 1911. Serial No. 662,710.

To all whom it may concern:

Be it known that we, WESLEY J. VONDRACEK and CYRIL C. SLAPNICKA, citizens of the United States of America, residing at 5 Cedar Rapids, in the county of Linn and State of Iowa, have invented certain new and useful Improvements in Oil-Burners, of which the following is a specification, reference being had therein to the accompanying drawing.

This invention relates to certain new and useful improvements in oil burners, and more particularly to a kerosene burner that can be attached to an ordinary cook stove 10 or range, but which in principle is also applicable to heaters and furnaces.

The invention has for its object to provide a burner of this type in which novel and effective means are provided for obtaining a proper mixture of the air and gas to obtain perfect combustion, and in which means is provided for admitting a current of air from the exterior to the combustion chamber to increase the intensity of the 25 flame.

A practical embodiment of our invention is illustrated in the accompanying drawing which shows a central vertical sectional view of an oil burner constructed in accordance 30 with our invention, and in describing the invention in detail, reference will be had to said drawing, like numerals being used throughout the description to designate like parts in the drawing.

An embodiment of the invention involves the provision of a main combustion chamber 5 inclosed by a casing 6 which may be cast integral with a hot plate, cover or ring 7, and which is provided with an annular 40 seat 8 for the reception of a circular plate or lid 9. In practice, the hot plate or ring is provided with supplemental rings so that the burner may be adapted to any sized opening in a stove, but as the provision of 45 such supplemental rings form no part of the invention, the same has not been shown in the drawings.

The outer shell or casing 6 is provided centrally of its bottom 10 with an aperture 50 11, and is provided in its wall at a point adjacent the bottom, with a plurality of flame outlet openings 12, as many of which may be provided as may be desired. Mounted in the opening 11 and extending upwardly into the combustion chamber 5 is a cylindrical casing 14 provided near its lower

end with an annular flange 15 which rests upon the bottom of the outer shell or casing 6 and forms a support for the cylindrical casing 14, the latter extending some distance below the bottom 10, and provided in its lower end with a valve 16 of any approved construction, by means of which the admission of air into the cylindrical casing 14 is regulated and controlled.

The cylindrical casing 14 carries a dish-shaped casing 17 which provides the oil chamber, which chamber is preferably provided with a packing or filling 18 which in practice we have generally made in the form of steel shavings, though any other suitable packing may, it is evident, be employed. The top 19 of the casing 17 is provided with an annular depressed portion 20 constituting a pan, and in which is placed a wick 21 70 75 The said top is also provided with outlets 22, as many of which may be provided as desired, and which are arranged circumferentially on the top at a point close to the cylindrical casing 14.

The cylindrical casing 14 is provided near its upper end, at a point directly above the top 19 of the casing 17 with a plurality of air outlet ports 23, establishing communication between the chamber in the cylindrical casing 14 and the carbureting chamber 24 located around the upper end of the casing 14. This carbureting chamber 24 is provided by means of an inverted cup-shaped shell 25 which rests upon the casing 17 and 80 85 is provided in its top with a central opening 26 leading to the mixing chamber 27, the latter being formed by an inverted cup-shaped shell 28 that is supported on a ledge 29 of the shell 25, and which shell 28 is provided 90 adjacent its lower end with a plurality of outlet ports 30 establishing communication 95 between the mixing chamber 27 and the combustion chamber 5.

Oil is fed to the oil chamber within the 100 casing 17 through a supply pipe 31 led in through the side wall of shell 6 and in through the bottom of the shell 17, the supply pipe leading to a suitably located source of supply (not shown) and controlled by a 105 supply pipe, said valve also not being shown.

Centrally of the lid or cover 9 is a depressed portion 32 on which is mounted a 110 rotatable controlling valve 33 by means of which the air admitted to the combustion chamber may be regulated and controlled.

The depressed portion of the lid or cover 9 and the valve 33 carried thereby fit over the upper end of a central rod 34 which turns in said depressed portion 32 and the lower apertured end of the shell 14 and carries with it when turned, the valves 16 and 33, so that said valves may be operated simultaneously. In this connection however, we wish to be understood that we do not limit ourselves to the operation of these two valves simultaneously, since obviously, each valve may be operated independently of the other if desired.

In operation, the burner is set in a stove 15 or range in place of the ordinary covers, and when it is desired to light the burner, the valve (not shown) in the supply pipe is opened, admitting oil through the pipe 31 to the oil chamber within the casing 17, the 20 oil passing up through the perforations 22 down to the asbestos wick 21. When the wick is saturated, the cover 9 is lifted, the wick lighted, and the cover then replaced. The burning of the oil from the wick 31 25 heats the oil within the chamber or casing 17 so that the oil is vaporized and the vapor passes up through perforations 22 and meets with a current of air entering through the lower end of casing 14 and passes into chamber 24 through openings or ports 23. Thus 30 the air and vapor meet and mix in chamber 24 and the mixture passes up through opening 26 and is further mixed within chamber 27, escaping therefrom through openings or ports 30 and is ignited in the combustion chamber 5. An upper current of air 35 is introduced through the openings in valve 33 and depressed portion 32 of the lid, and passing downward, meets the mixture of air 40 and gas as it comes through perforations 30 and causes it to be burned with an intense heat. The flame passes downward in the combustion chamber 5 and out through the 45 perforations or openings 12, and combustion is completed outside of the chamber 5. As stated, in starting, the oil is admitted to saturate the wick, which is then lighted, and this in turn ignites the vapor as it begins to form, and as the oil in the wick is burned 50 and the flame goes out, the valve (not shown) in the supply pipe is opened which admits oil to the heated oil chamber within the casing 17 and this oil instantly vaporizes and passes through the mixing chamber to 55 the combustion chamber. The valves 16 and 33 regulate the air supply, being but slightly opened when a small flame is desired, and where a large flame is desired, being opened

fully so as to admit the desired amount of air to effect perfect combustion.

Having fully described our invention, what we claim as new and desire to secure by Letters Patent is:—

1. In an oil burner, a ring carrying a depending outer shell and having a seat at the upper edge of said shell, a lid or cover fitting said seat and having a depressed central portion provided with an opening, a valve controlling said opening, a cylindrical casing mounted on the bottom of said outer shell and extending below said bottom and having an opening in its lower end and provided with outlet ports near its upper end, an oil chamber formed around said cylindrical casing within the outer shell and having its upper face formed with a pan, two superposed shells supported above said oil chamber and having communication with each other and with the oil chamber, and an oil supply pipe leading through the outer shell and into said oil chamber.

2. In an oil burner, a ring provided with a depending shell having a central apertured bottom, a cylindrical casing mounted in said bottom and extending below the bottom, a casing carried by said cylindrical casing and having its top face provided with a pan, said top face provided with outlets arranged around the cylindrical casing, two superposed shells supported on the top of said second named casing, a lid supported within said ring and having an air inlet, a valve for controlling said inlet, a valve for controlling the inlet of air to said cylindrical casing, and means connecting said valves whereby they may be operated in unison.

3. In an oil burner, a ring having a depending outer shell, a cylindrical casing mounted in the bottom of said shell, a casing surrounding said cylindrical casing and forming an oil chamber, said second named casing having a pan formed in the top thereof and also having openings in said top, two superposed casings supported by the casing surrounding the cylindrical casing, and connected valves controlling the admission of air to the outer shell and to the cylindrical casing.

In testimony whereof we affix our signatures in the presence of two witnesses.

WESLEY J. VONDRACEK.
CYRIL C. SLAPNICKA.
